UNITED STATES PATENT OFFICE.

ALVIN D. BUCK, OF HITES, PENNSYLVANIA.

SHUTTER-ADJUSTER.

SPECIFICATION forming part of Letters Patent No. 633,788, dated September 26, 1899.

Application filed June 24, 1899. Serial No. 721,708. (No model.)

To all whom it may concern:

Be it known that I, ALVIN D. BUCK, a citizen of the United States of America, residing at Hites, in the county of Allegheny and State of Pennsylvania, have invented certain new and useful Improvements in Window-Shutter Adjusters and Holders, of which the following is a specification, reference being had therein to the accompanying drawings.

10 This invention relates to certain new and useful improvements in shutter-locks, and more particularly to that class known as "outside" shutters.

The invention has for its object to construct 15 a lock, which will be hereinafter described, that will retain the shutter at any angle desired and one that may be easily operated.

Briefly described, the invention consists of a 20 segmental rack formed with a series of radial notches, the rack being rigidly secured to the window-sill, a keeper having its ends formed at an angle and which is secured to the inner 25 face of the window-shutter, a gravity-pawl pivotally secured at one end in the said keeper, and a handle formed integral with the said 30 pawl for operating the same, the operation of the pawl being limited by one end of the keeper.

The invention finally consists in the novel 35 construction, combination, and arrangement of parts to be hereinafter more fully described, and specifically pointed out in the claim.

In describing the invention in detail reference is had to the accompanying drawings, 40 forming a part of this specification, wherein like numerals of reference indicate corresponding parts throughout the several views, in which—

45 Figure 1 is a perspective view of a portion of the building, window frame, sash, and shutter, provided with my improved lock. Fig. 2 is a transverse vertical sectional view taken on the line 2 2 of Fig. 1. Fig. 3 is a plan view of the segmental locking-rack. Fig. 4 is a front view of the same. Fig. 5 is a vertical sectional view taken on the line 5 5 of Fig. 3. Fig. 6 is a top view of the keeper. Fig. 7 is a rear elevation of the same. Fig. 8 50 is a detail view of the gravity-pawl. Fig. 9 is an enlarged vertical sectional view taken on the line 9 9 of Fig. 2.

Referring to the drawings by reference-numerals, 1 indicates the window-sash, and 2 the window-frame, having formed therein a 55 recess 3.

The reference-numeral 4 represents the segmental locking-rack, said rack being connected by a bar 5, formed integral therewith, said bar having arranged thereon a boss 6 60 and having formed therein apertures 7. Radially-extending notches 8 are formed upon the upper face of the segmental rack.

The reference-numeral 9 indicates a pivot secured to the under face of the shutter and 65 adapted to engage in the boss 6 of the bar 5.

The reference-numeral 10 represents a keeper having formed at the ends thereof apertured lugs 11, providing fastening means for securing the same to the inner face of the 70 shutter, the said keeper being provided on its one face with a pin 12.

The reference-numeral 13 indicates a gravity-pawl having a curved handle 14, a lower engaging face 15, and an apertured head 16, 75 said head forming a pivotal connection with the pin 12 of the keeper, the lower engaging face being adapted to engage the notches 8 of the segmental rack. The recess 3 in the frame is adapted to receive the keeper and to 80 admit the shutter to be brought to the position flush with the front face of the frame. The gravity-pawl is so arranged within the keeper as to allow the handle 14 to extend upwardly above the keeper in order that the 85 same may be easily accessible.

The many advantages that are obtained by the use of my improved shutter-lock will be readily understood from the foregoing description; but particular attention is directed 90 to the fact that various changes may be made in the details of construction without departing from the general spirit of my invention.

Having thus fully described my invention, what I claim as new, and desire to secure by 95 Letters Patent, is—

In a shutter-lock, the combination with a window sill, frame and shutter, the said frame having formed therein a recess, of a segmental rack provided with a series of radial 100 notches, a bar formed integral with the ends of the said rack adapted to be secured to the said frame for supporting the said rack, a boss arranged on the said bar adapted to piv-

totally support the said shutter, a keeper consisting of an elongated metallic strip having each end bent at an angle and secured to the inner face of the said shutter adapted to be seated within the said recess when the shutter is closed, a pin formed integral with the said keeper, a gravity-pawl having one end mounted on the said pin adapted to engage the said notches for fastening the shutter at the desired angle, and a curved handle formed

integral with the said pawl and adapted to engage one of the angle ends of the said keeper for limiting the movement of the pawl, substantially as set forth.

In testimony whereof I affix my signature ¹⁵ in the presence of two witnesses.

ALVIN D. BUCK.
